UNITED STATES PATENT OFFICE.

POPKO REINDER DIJKSTERHUIS, OF EINDHOVEN, NETHERLANDS, ASSIGNOR, BY
MESNE ASSIGNMENTS, TO RADIO CORPORATION OF AMERICA, OF NEW YORK, N. Y.,
A CORPORATION OF NEW YORK.

DISCHARGE TUBE.

Application filed February 8, 1926, Serial No. 86,845, and in the Netherlands April 30, 1925.

Electric discharge tubes are known which comprise a hollow cathode, for example, a cylindrical oxide cathode heated by an electric heating element located inside the cathode, and in which the leading-in wires for the said element, those for the cathode and those for the other electrodes pass through a single so-called "pinch".

The invention has for its object to free 10 the functioning of such a discharge tube from the disturbing electromagnetic as well as electro-static inductive influence originated by the said heating element. It is obvious that in particular the controlling 15 electrode must be protected against these inductive influences.

According to the invention, in order to realize this object, the leading-in wires for the heating element, for the cathode and for 20 the other electrodes are led inwards through a single "pinch", the leading-in wires for the heating element are located close to each other at one extreme side of the pinch, whereas the leading-in wires for the electrodes, in particular that for the controlling 25 grid, if any, are located at the other end of the pinch so as to be as far remote as possible from the other leading-in wires.

Without any difficulty the heating element 30 can be fed in this case with alternating current without the anode current being modulated in any detrimental manner by the frequency of this alternating current.

In most cases it is advisable to provide a 35 screening device near the opening of the cathode through which passes the heating element, between the other electrodes of the tube and that portion of the heating element which extends outside the cathode.

The cathode is preferably made of chrome 40 iron, said material being easily deprived of occluded gases and being readily sealed to glass, which permits of sealing the open end of the cathode to the glass envelope of the 45 tube so that the interior space of the cathode is accessible from the outside. Consequently the heating element can easily be replaced by another without any necessity of taking the tube to pieces.

If in addition the anode is also made of 50 chrome iron and if the tube is constructed so as to have the greater portion of its outer wall constituted by the anode, a robust whole is obtained which neither has a fragile glass

bulb, nor comprises a filament arranged inside the tube. 55

The accompanying drawing represents, by way of example, an embodiment of the invention.

In the tube illustrated all the leading-in 60 wires pass only through a single pinch on one side of the tube and moreover the cathode 1 is open on both sides, which affords the possibility of keeping a filament 4 stretched by means of a spring 21. 65

The current is supplied to the incandescent body 4 by conductors 5 and 6 which pass through a pinch 15 to leading-in wires 17 and 18; the conductors 5 and 6 pass through one side of the pinch whereas a leading-in 70 wire 10 for the grid 2 passes through the opposite side of this pinch in order to keep the conductor 10 as far as possible apart from the conductors which are traversed by the alternating current for heating the filament. 75

In order to keep the grid 2 itself as much as possible out of the induction zone of the incandescent body 4, the cathode 1 is made materially longer than this incandescent 80 body and also materially longer than the grid 2. The cathode is preferably made of chrome iron and that portion of the outer surface which has to participate actively in the emission of electrons, is coated with a 85 suitable active layer. The lead in wire 11 is connected to the anode 3.

The conductive connection with the cathode is constituted by a metal clip 19 secured to a metal carrying rod 20 which passes 90 through the pinch 15 and which supports at its top the spring 21 already mentioned. Thus a conductive connection is also obtained between the cathode 1 and the centre of the filament 4, which decreases still more 95 the influence of the period of the alternating current passing through the filament 4.

What I claim is:

1. In a discharge tube, anode, cathode and grid electrodes, a single pinch for the leads 100 to the tube, a separate electrical heating element disposed adjacent to and heating the cathode, leads to said heating element, said leads being disposed at one end of said single pinch, and a grid lead passing thru 105 said pinch, said grid lead being positioned at the end of the pinch opposite to the leads to the heating element.

2. A discharge tube having anode, cathode and grid electrodes, a single pinch for the leads to the tube, a separate electrical heating element disposed adjacent to and heating the cathode, leads to said heating element, said leads being disposed at one end of said single pinch, a lead passing thru said pinch and connected to the grid, said grid lead being positioned at the end of the pinch opposite to the leads to the heating element, and a lead passing thru said pinch connected to the cathode. 40
3. A discharge tube having anode, cathode and grid electrodes, a single pinch for the leads to the tube, a separate electrical heating element disposed adjacent to and heating the cathode, leads to said heating element, said leads being disposed at one end of said single pinch, a lead passing thru said pinch and connected to the grid, said grid lead being positioned at the end of the pinch opposite to the leads to the heating element, and a lead passing thru said pinch connected to the cathode. 45
4. A discharge tube having anode, cathode and grid electrodes, said cathode being cylindrical, a single pinch for the leads to the tube, a separate V shaped electrical heating element disposed within the cathode, leads to said heating element, a support for said heating element positioned outside of the cylindrical cathode, said support having a portion extending within the end of the cathode opposite to the heating element 50
5. A discharge tube having anode, cathode and grid electrodes, said cathode being cylindrical, a single pinch for the leads to the tube, a separate V shaped electrical heating element disposed within the cathode, leads to said heating element, a support for said heating element positioned outside of the cylindrical cathode, said support having a portion extending within the end of the cathode opposite to the heating element 55
6. A discharge tube having anode, cathode and grid electrodes, said electrodes being disposed eccentrically within the tube, a single pinch for the leads to the tube, a separate heating element disposed adjacent to and heating the cathode, leads to said heating element, said leads being disposed at one end of the single pinch, and a grid lead passing thru said pinch, said grid lead being disposed at the end of the pinch opposite to the heating element leads, said grid lead extending within the tube eccentrically opposite from the electrodes and being connected to the end of the grid which is farthest from the heating element leads. 60
- 30 the tube, a separate electrical heating element disposed within the cathode, the length of the cathode being considerably longer than the heating element thereby serving as an electrical shield between the grid and 70
- 35 the heating element leads to said heating element, said leads being disposed at one end of said single pinch, and a grid lead passing thru said pinch, said grid lead being

positioned at the end of the pinch opposite to the leads to the heating element. 40

In testimony whereof I affix my signature, at the city of Eindhoven, this 16th day of January, A. D. 1926.

POPKO REINDER DIJKSTERHUIS.
